His Attorney.

UNITED STATES PATENT OFFICE

2,017,707

FLOW RETARDER FOR COMPRESSORS

Harry A. Whitesel, Fort Wayne, Ind., assignor to
General Electric Company, a corporation of
New York

Application January 11, 1934, Serial No. 706,219

9 Claims. (Cl. 62—1)

My invention relates to flow retarders for refrigerating machines, and more particularly to arrangements permitting the removal of connectors for pressure responsive devices employed on such machines.

Refrigerating machines are frequently provided with pressure responsive devices for limiting the pressure which may be developed on the high pressure side of the machine. These devices stop the operation of the machine when a predetermined high pressure has been reached. It sometimes becomes necessary to remove the pressure responsive device in order to readjust or repair it, and on such occasions it is necessary to provide some means for stopping the loss of refrigerant gas when the pressure connection is opened. The flow of gas may be stopped by a valve arranged between the high pressure side and the connection for the pressure responsive device. However, there is some danger attending the use of such an arrangement since if the valve is left closed after the machine is again placed in operation dangerous pressures may result since the safety device would be rendered non-responsive to the pressure in the machine.

It is an object of my invention to provide a refrigerating machine having a pressure limiting device, the connections of which may be removed without substantial loss of refrigerant and without danger of completely cutting off the connection between the refrigerating machine and the pressure responsive device when the device is reconnected.

Another object of my invention is to provide a flow responsive device for limiting the flow of compressed gas, as for example, from a refrigerating machine when a mechanism such as a pressure responsive device is removed therefrom.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawing in which Fig. 1 is a side sectional elevation of a refrigerating machine partly in section provided with a flow retarding device embodying my invention, and Fig. 2 is an enlarged detail sectional view of the flow retarding device shown in Fig. 1.

Referring now to the drawing, in Fig. 1 I have shown a refrigerating machine including a closed compression casing 10 mounted on a base 11

which in this case is the removable top of a refrigerator cabinet. Within the casing 10 is arranged a motor and compressor unit 12 resiliently mounted on springs 13. Refrigerant is compressed within the casing 10 and flows through a connection 14 to a condenser 15 where it is liquefied and flows through a conduit 16 to a flow controlling device or float valve 17, from whence it flows in regulated quantities through a conduit 18 to an evaporator 19 which is supported on legs 20 below the top 11. The liquid refrigerant within the evaporator 19 is vaporized upon absorption of heat from the interior of the refrigerator cabinet, and the vapor collects in a header 21 from which it is withdrawn through a suction conduit 22 and returns to the compressor within the casing 10. A motor 23 driving a fan 23a is provided to cool the casing 10 and the condenser 15. A control switch 24 is provided to start and stop the motor of the unit 12 in accordance with the temperature of the evaporator 19, or the space being cooled thereby.

Under some conditions of operation, such as might be produced by too high a temperature of the air circulated about the casing 10 and the condenser 15, excessive pressures might be generated within the casing and condenser which are on the high pressure side of the refrigerating system. In order to prevent this, the control 24 is provided with an expandible bellows 25 connected by a conduit 26 with the casing 10. When a predetermined safe high pressure limit is reached within the casing 10 and the condenser, the bellows 25 causes the control 24 to operate and stop the operation of the refrigerating machine until the pressure in the casing 10 is reduced to a safe limit. It is sometimes necessary in order to readjust or repair the control 24 and the bellows 25 to disconnect the conduit 26 from the casing 10. In such case it is apparent that some arrangement must be provided to prevent the escape of compressed refrigerant from the high pressure side of the system.

In accordance with my invention I provide a connection whereby the conduit leading to the pressure responsive control may readily be detached or removed from the high pressure side of the refrigerating machine, and within the connection I arrange an orifice or a plurality of orifices of such dimensions that while the pressure responsive device is connected to the high pressure side of the machine, there will be ample communication to provide proper operation of the pressure responsive device, and when the pressure responsive mechanism is removed from

the machine the flow of gas through the orifices will be so limited or retarded that only a small amount of gas will leak out of the refrigerating machine.

5 In the embodiment of my invention illustrated in the drawing, and particularly as shown in Fig. 2, I provide a hollow bushing or connection 27 welded at 28 or otherwise secured to the casing 10. The connection 27 is provided with a screw threaded portion 29 and the conduit 26 is securely held in place by a threaded sleeve 31 having a shoulder 32 retaining a flared portion 30 of the conduit 26 against a beveled edge 33 of the connection 27 to provide a pressure tight joint. In order to prevent any substantial leakage of compressed gas from one casing 10 when the conduit 26 is removed, I arrange one or more cup-shaped inserts 34 within the connection 27 to provide a series of chambers 34a. Each of the inserts 34 is provided with an orifice 35 in the center thereof affording communication between the chambers 34a, and a fine mesh screen 36 prevents clogging of these orifices by particles which might be present in the refrigerating machine. The inserts 34 are held securely in place against a shoulder 37 formed by a reduced portion of the bore of the connector, the inner edge of the connector being swaged over against a ring 38 which bears against the screen 36 and clamps the screen and the inserts against the shoulder 37.

In the operation of the refrigerating machine shown, when it is desired to remove the pressure responsive control the sleeve 31 is unscrewed and the conduit 26 removed from the connection 27. Refrigerant vapor under pressure is discharged through the orifices 35, and because of the high pressure and turbulence produced at the orifices and in the refrigerant vapor isolated in the chambers 34a, the flow of the vapor is retarded and any substantial loss of vapor is prevented over a considerable period of time. This flow retarding connection will also permit the escape of air or other non-condensable gas which may be trapped within the refrigerating system when the conduit 26 is removed from the connection 27.

It is apparent from the foregoing that I have provided a simple and rugged device for connecting pressure responsive mechanism such as collapsible bellows for operating safety overload switches, or the like, which prevents any substantial loss of refrigerant from the system when for any reason it becomes necessary to disconnect the pressure responsive device.

55 While I have described a particular embodiment of my invention as applied to a compression refrigerating machine other uses will be readily apparent to those skilled in the art, and I do not desire my invention to be limited to the specific embodiment shown and described, and I intend in the appended claims to cover all modifications within the spirit and scope of my invention.

What I claim as new and desire to secure by Letters Patent of the United States, is:

60 1. A refrigerating machine containing fluid under pressure, a pressure responsive device, a detachable connection between said device and said refrigerating machine, and means for isolating a portion of the fluid passing to said connection and setting up turbulent currents therein to minimize the escape of fluid from said machine through said connection when said device is disconnected from said machine.

70 2. A refrigerating machine containing a fluid under pressure, means including a pressure re-

sponsive device communicating with said refrigerating machine for limiting the pressure of the fluid in said refrigerating machine, means for detachably connecting said device to said machine, and means including a plurality of orifices arranged in series between said refrigerating machine and said connecting means for retarding the flow of compressed gas from said machine when said device is detached.

75 3. A refrigerating machine including a closed compression casing, a pressure responsive device for limiting the pressure within said casing, a conduit providing communication between said casing and said device, means for detachably connecting said conduit between said device and said casing, and means including a plurality of orifices arranged between said casing and said connecting means for limiting the flow of compressed gas from said casing when said connecting means is detached.

80 4. A refrigerating machine containing a fluid under pressure, and means including a pressure responsive device and a detachable conduit communicating with said refrigerating machine for limiting the pressure within said refrigerating machine, said means including a connector having a plurality of cup-shaped inserts provided with orifices affording communication between said conduit and said connector for retarding the flow of gas from said machine when said conduit is detached.

85 5. A refrigerating machine including a closed compression casing, means including a compressor for compressing gas within said casing, a pressure responsive device including a collapsible bellows for stopping said compressing means in response to a predetermined high pressure within said casing, and a detachable conduit connecting said casing and said bellows, and means including an orifice for isolating a portion of the gas passing to said connection and setting up turbulent currents therein to minimize the escape of gas from said machine when said bellows is disconnected from said casing.

90 6. A refrigerating machine containing a fluid under pressure, a pressure responsive device communicating with said refrigerating machine, means for detachably connecting said device to said machine, and means including a plurality of orifices arranged in series between said refrigerating machine and said connecting means for retarding the flow of compressed gas from said machine when said device is detached.

95 7. A refrigerating machine containing a fluid under pressure, a pressure responsive device communicating with said refrigerating machine, means including a hollow bushing for detachably connecting said device to said machine, and means including a plurality of cup-shaped inserts within said bushing for isolating a portion of the fluid passing through said bushing and setting up turbulent currents therein to minimize the escape of fluid from said machine through said bushing when said device is disconnected from said machine.

100 8. A refrigerating machine containing a fluid under pressure, a pressure responsive device communicating with said refrigerating machine, means including a hollow bushing for detachably connecting said device to said machine, and means including a plurality of cup-shaped inserts within said bushing for isolating a portion of the fluid passing through said bushing and setting up turbulent currents therein to minimize

the escape of fluid from said machine through said bushing when said device is disconnected from said machine, each of said inserts having an orifice therein, said orifices being arranged in 5 series and affording communication between the ends of said bushing.

9. A refrigerating machine containing a fluid under pressure, a pressure responsive device communicating with said refrigerating machine, 10 means including a hollow bushing having an annular shoulder formed therein for detachably

connecting said device to said machine, means including a plurality of cup-shaped inserts arranged within said bushing for retarding the flow of compressed gas from said machine when said device is detached, each of said inserts having an orifice therein, said orifices affording a communication between the ends of said bushing, means including a screen for preventing clogging of said orifices, and means for holding said inserts against said annular shoulder. 5
